ELECTRON DISCHARGE DEVICE

Ross K. Gessford, Emporium, Pa., assignor to
 Sylvania Electric Products Inc., Emporium, Pa.,
 a corporation of Massachusetts

Application June 25, 1945, Serial No. 601,398

9 Claims. (Cl. 250—159)

1

My invention relates to an electron discharge device and to a clamping or support arrangement for an element of an electron discharge device, such as a deflector plate for a cathode ray tube.

Electron discharge devices, such as cathode ray tubes, have usually included an electron gun supported in an envelope, which produces a beam of electrons which impinge on a screen. In order to control the direction of flow of the beam of electrons, it is customary to provide deflection plates which usually take the form of two pairs of spaced plates, so that when a potential is properly applied to the plates, the electron beam will be made to scan the screen. Such an electron discharge device as a cathode ray tube also usually includes supporting members such as spaced column members upon which the various plates and other portions of the device are supported. In such devices the deflection plate has usually been supported from the supporting column through a bracket, and once the size of the bracket is designed, the deflection plate is permanently positioned in relation to the supporting columns and the electron beam, the direction of which is to be determined by the potential on the plates. It sometimes happens, however, that it is desired to change the position of the deflection plate in a particular tube construction, and it is also desirable to provide a particular plate construction which may be made in large quantities and which may be employed in different types of tubes.

It is, therefore, an object of my invention to provide an improved electron discharge device with an arrangement for supporting a plate member in a manner which will facilitate the fabrication of the electron discharge device.

Another object of my invention is to provide an improved deflection plate mounting arrangement for an electron discharge device, such as a cathode ray tube.

Further objects and advantages of my invention will become apparent from the following description referring to the accompanying drawing, and the features of novelty which characterize my invention will be pointed out with particularity in the claims annexed to and forming a part of this specification.

In the drawing, Fig. 1 is a top plan view of an electron discharge device which is provided with an embodiment of my invention; Fig. 2 is a side view of the tube construction of Fig. 1; Fig. 3 is an exploded perspective view of the pair of clamp members which are employed to support the deflection plates in the discharge device construction illustrated in Fig. 1 and Fig. 2; Fig. 4 is a sectional view taken along the lines of 4—4 of Fig. 2; and Fig. 5 is a diagrammatic view of an electron discharge device, such as a

2

cathode ray tube of the type with which my invention may be employed.

Referring to Fig. 1 and Fig. 2 of the drawing, I have illustrated a tube mount for an electron discharge device which is particularly suitable for a cathode ray tube which includes a tubular portion 1, which may be considered as the upper portion of a conventional electron gun which is conventional to employ in such an electron discharge device. In order to support the various parts of the tube mount in spaced relation to each other, there is provided supporting means or spaced supporting columns 2, 3, 4, and 5. Spaced plate members 6 and 7 are provided, on the periphery of which are placed a plurality of supporting arrangements or snubbers 8 which position the end of the tube mount within an envelope 9, which is diagrammatically illustrated in Fig. 5.

It will be understood that a beam of electrons is provided by the electron gun, which electrons pass through the tube 1, and in order to control the path of the electron beam so that the beam may scan a screen 10, which is positioned at the end of the envelope 9, there are provided a pair of deflection plates 11 and 12 which are spaced from each other and a second pair of deflection plates axially spaced from the first pair 11 and 12, one of said second pair of plates being identified by the numeral 13. It will be seen that the plane of the plates 11 and 12 are at right angles to the plane of the plates 13 so that the path of the electron beam may be controlled in two directions.

In order to provide a supporting arrangement for the deflection plates so that the distance between the plates may be varied for any particular tube construction and so that the position of the plates may be changed with respect to the supporting columns and the electron beam, I provide a first clamp member 14 which is adapted to be relatively rigidly attached to the supporting columns 2 and 3 and a second clamp member 15 which is adapted to be relatively rigidly attached to the deflection plates, such clamp members being particularly shown in Fig. 3. It will be understood that each one of the deflection plates is supported on adjacent pairs of columns in the same manner, and so the supporting arrangement for only one of the deflection plates will be described.

As will be seen in Fig. 3, the clamp member 14 has a U-shaped construction or a relatively flat portion 16 with two right-angularly or depending flanges 17, the purpose of which will become apparent as the following description proceeds. Similarly, the clamp member 15 is substantially U-shaped and has a relatively flat portion 18 with two angularly extending flanges 19. In order to support clamp member 14 on

a pair of spaced supporting columns 2 and 3, a relatively flat portion 16 is provided with collars 20 through which pass the columns 2 and 3, as will be clearly seen in Figs. 1 and 2. The collars 20, when the clamp 14 is suitably positioned with respect to the rest of the mount, may be crimped so that the clamp 14 may be relatively rigidly mounted with respect to the supporting columns 2 and 3. Also, the plate 11 may be suitably formed or fabricated and during this operation the clamp 15 may be relatively rigidly attached to the deflection plate 11 in any suitable manner, such as by spot welding, as is indicated by the numeral 21.

In the fabrication of the mount of an electron discharge device as that illustrated in a drawing, when the deflection plate is suitably positioned with the remainder of the structure, the pair of clamps 14 and 15 will be nested or telescopically arranged, and the adjacent outwardly projecting flanges 17 and 19 may be attached together in any suitable manner, such as by spot welding, as is indicated by the numeral 21^a in Fig. 4. Referring also to Fig. 2, it will be seen that the pair of clamp members for supporting the deflection plate 13 are arranged with the outwardly extending flanges 19 of the clamp 15 placed over the outer surface of the depending flanges 17 of the clamp member 14. It will be understood that the pair of clamp members including the first member 14 attached to the supporting columns 2 and 3 and the second clamp member 15 which is attached to its deflection plate may be so designed that the adjacent flanges 17 and 19 fit relatively tightly together.

In view of my improved supporting arrangement for the deflection plates, the position of the deflection plates may be varied by merely changing the relative relationship between the cooperating flanges 17 and 19. For example, in Fig. 4 I have illustrated in full line the relationship of the supporting flanges with the deflection plate positioned as illustrated, and in dotted lines the deflection plate and supporting flanges are shown in a slightly different position, and the deflection plate may be relatively rigidly supported in this position by merely spot welding the flanges 17 and 19 together when they are in the position illustrated in Fig. 4 in dotted lines.

My improved supporting arrangement for deflection plates also provides a convenient way for electrically connecting the deflection plate to an external circuit, and as will be seen in Figs. 1 and 2, a pig-tail or connecting conductor 22 is attached to the clamp members at 23 and is, in turn, connected to a line conductor at 24, which passes out through the supporting columns 2 and 5.

Although I have shown and described particular embodiments of my invention, I do not desire to be limited to the particular embodiments described, and I intend, in the appended claims, to cover all modifications which do not depart from the spirit and scope of my invention.

What I claim as new and desire to secure by Letters Patent of the United States is:

1. An electron discharge device including a plate member, a support, a first U-shaped clamp member, a second U-shaped clamp member, means for attaching said first clamp member to said plate and said second clamp member to said support, said U-shaped members being relatively

telescopically arranged and attached together for positioning and supporting said plate member with respect to said support.

2. An electron discharge device including means providing a beam of electrons, a deflection plate positioned laterally of the normal course of said beam, a support, a flat projection secured to and extending from said support, and a flat projection extending perpendicularly from said plate, said projections being joined in overlapping face-to-face contact.

3. An electron discharge device including means providing a beam of electrons, a deflection plate positioned generally parallel to the undeflected course of said beam, a support, a flat member projecting from said support and lying in a plane substantially parallel to said course, and a second flat member extending substantially perpendicularly from the rear of said plate and in a plane substantially parallel to said beam, said members being joined in face-to-face contact and in any desired relative position.

4. An electron beam tube including a deflection plate and a support each having a pair of flat spaced-apart portions, and rigid conductive lap-joints between said portions lying in planes parallel to the undeflected course of said beam.

5. An electron beam tube according to claim 4 wherein one pair of portions embraces the other pair.

6. An electron beam tube according to claim 4 including pairs of deflection plates properly spaced apart by said joints.

7. The method of mounting an electrode on a support in an electron discharge device including the steps of providing the electrode with a flat metal extension, similarly providing said support with a flat metal extension and conductively joining said extensions in overlapping contact and in any desired relative position.

8. The method of mounting a deflection plate in an electron beam tube which comprises the steps of providing the plate with a rearward flat extension lying in a plane parallel to the electron beam, similarly providing a support in the electron beam tube with a flat metal extension lying in a plane parallel to the beam, and conductively joining said extensions in any desired relative position to locate said plate in the proper axial, radial and angular position in relation to the undeflected course of the beam.

9. The method of mounting a generally flat plate in an electron discharge tube comprising the steps of providing the plate with a parallel pair of flat extensions substantially at right angles to the surface of the plate, providing a nesting pair of supporting parts, and welding said extensions to said supporting parts for properly orienting said plate.
